UNITED STATES PATENT OFFICE

147,767

DESIGN FOR A PICTURE FRAME

Alwin L. Suman, Sierra Madre, Calif.

Application August 17, 1946, Serial No. 132,615

Term of patent 3½ years

(Cl. D29—20)

To all whom it may concern:

Be it known that I, Alwin L. Suman, a citizen of the United States and residing at Sierra Madre, in the county of Los Angeles, State of California, have invented a new, original, and ornamental Design for a Picture Frame, of which the following is a specification, reference being had to the accompanying drawing, forming part thereof, in which:

Fig. 1 is a perspective view of a picture frame showing my new design, and

Fig. 2 is a side elevation thereof.

I claim:

The ornamental design for a picture frame, substantially as shown.

ALWIN L. SUMAN.
